United States Patent Office

Des. 216,453

Patented Jan. 13, 1970

216,453

BRASSIERE

Sam Guberman, Bayonne, N.J., assignor to Maidenform,
Inc., New York, N.Y., a corporation of New York

Filed Mar. 17, 1969, Ser. No. 16,294

Term of patent 7 years

Int. Cl. D2—02

U.S. Cl. D2—24

The figure is a front perspective view of a brassiere showing my new design, the back of the brassiere being conventional.

I claim:

The ornamental design for a brassiere, as shown and described.
